(57) **CLAIM**

The ornamental design for an electric bike, as shown and described.

DESCRIPTION

FIG. 1 is a top, front and right side perspective view of an electric bike showing my new design;

FIG. 2 is a bottom, rear and left side perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is an enlarged detail view of area 9 in FIG. 1;

FIG. 10 is an enlarged detail view of area 10 in FIG. 1;

FIG. 11 is an enlarged detail view of area 11 in FIG. 1;

FIG. 12 is an enlarged detail view of area 12 in FIG. 1;

FIG. 13 is an enlarged detail view of area 13 in FIG. 1;

FIG. 14 is an enlarged detail view of area 14 in FIG. 1;

FIG. 15 is an enlarged detail view of area 15 in FIG. 2;

FIG. 16 is an enlarged detail view of area 16 in FIG. 2;

FIG. 17 is an enlarged detail view of area 17 in FIG. 2;

FIG. 18 is an enlarged detail view of area 18 in FIG. 2; and,

FIG. 19 is an enlarged detail view of area 19 in FIG. 3.

The broken lines in the drawings illustrate the portions of the electric bike, which form no part of the claimed design.

The dash-dot-dash broken lines in FIGS. 1-2 and 9-19 indicate the boundaries of the enlarged views and are used for annotative purposes only. They do not limit or define the scope of the claimed design.

1 Claim, 19 Drawing Sheets
